ASSIGNOR TO THE J. HENRY KOENIG COMPANY, OF CINCINNATI, OHIO, A COR-
PORATION OF OHIO.

CAN-LABELING MACHINE.

1,273,795.

Specification of Letters Patent.

Patented July 23, 1918.

Application filed March 21, 1918. Serial No. 223,827.

To all whom it may concern:

Be it known that we, FREDERICK T. VON WAHLDE and FRANK ARNOLD STIENS, citizens of the United States, and residing at 5 St. Bernard, in the county of Hamilton and State of Ohio, have invented a new and useful Improvement in Can-Labeling Machines, of which the following specification is a full disclosure.

10 Our invention relates to a can-labeling machine, and in particular to the means for applying a coating or stripe of glue completely around the periphery of the can before applying the label.

15 An object of the invention is to provide a can-labeling machine with simple and efficient means for applying a coating or stripe of glue or adhesive upon the can periphery and entirely around the same and at the 20 cover joint of the can, whereby a label can be secured to and around the can for covering and hermetically sealing the cover joint.

Another object of the invention is to provide a can-labeling machine with a rotating 25 glue distributing roll, adapted to be engaged by a can, together with means for holding the can at such roll engaging point or glue applying station and rotating the can while in contact with said glue distributing roll.

30 Another object of the invention relates to the combination of belt can conveyer means arranged to engage and advance a can over a track upon a glue distributing roll for applying a coating of glue to the 35 periphery of the can, and a stop device for holding the can at its gluing or pasting station, releasing by a successive can advance toward the gluing or pasting station.

Further objects and features, some relating 40 to structural details, will definitely appear from the detailed description of the accompanying drawings, illustrating a preferred embodiment of the invention, and forming a part of this specification. In the 45 drawings like characters of reference denote corresponding parts throughout the several views, of which:—

Figure 1 is a central vertical section of a can-labeling machine containing our improvement.

Fig. 2 is a section on line 2, 2, Fig. 1.

Paper cans or cylindrical paper containers are largely used for packing staple commodities in retail quantities as a means for 55 specializing particular brands through a

dealer to a user. The covers or caps of such packages or containers are sealed and secured to the body of the container by a label or wrapper. To make a hermetic seal around the cover joint, it is necessary to 60 gum or paste the label entirely around the periphery of the can and cover flange. Such method, aside from making a secure and tight closure, serves as a safety measure against fraud by refilling, as it requires the 65 label to be cut, or seal broken, before the cover can be removed. The usual method of opening is to cut the label around the can at the edge of the cover flange. Therefore as the entire surface of the label or can 70 around the cover joint is required to be pasted or gummed to make a seal as required, commercial can-labeling machines could not be used for the work, as such machines are adapted for spot pasting or gumming 75 the can and cross edge pasting the label.

With our invention a commercial can-labeling machine is available for the different methods of applying an adhesive, above 80 mentioned, and as the gluing mechanism only is herein concerned, a complete structure of the can-labeling machine is not exhibited in the views, and only so much of the structure is shown as will suffice to illustrate 85 the connection of the invention therewith, thus the label feeding and label cross edge pasting devices are eliminated from the drawings.

Referring to the drawings, 1 indicates a 90 skeleton frame structure upon which the various devices of the labeling machine are supported and secured, and includes the horizontal frame beams 2 as a table. A pair of bow-end supports 3 are fixed to each end 95 of the frame beams 2 projecting upwardly and inwardly, and the free end of each of said bow supports has a vertically slotted lug 4, to which the brackets 5 of the carrier frame 6 are adjustably secured. Each end 100 of the carrier frame 6 respectively provides journals for the shafts 7, said shafts each carrying a pair of pulleys 8. The pulleys 8 on each shaft are appropriately spaced from each other and in alignment with a companion pulley at the opposite end of the carrier frame, for respectively tracking a pair of can conveyer belts 9, 9. The belts 9, 9, are spaced to bring their belt runs upon and in frictional engagement with the op- 105 110

posite edges of the cans for conveying and rolling the cans from a feeding end to a discharge end upon a pair of track rails 10, 10, running longitudinally with and above the 5 horizontal frame beams 2. The spacing gage of the track rails are such a distance apart so as to interveningly receive the can gumming roll and labels. A can end guard rail 11 extends longitudinally above and 10 parallel with a relative track rail 10 for guiding the cans in their travel through the labeling machine. 12 indicates a can holding delivery tray disposed at an incline, at the receiving end of the machine, and 13 indicates a tray at the discharge end of the machine. The trays 12 and 13 are each hinged to a bracket fixed to a respective bow support, adapting the trays to be swung downwardly when not in use. The labels 14 15 in a stack, are supported upon the table 15 between the track rails 10, 10. The table is appropriately raised by ratchet feeding mechanism operating at timed intervals with the release of each can from the delivery tray 12, as the can starts in its travel to be labeled. The table is elevated or fed upwardly to always bring the uppermost label of the stack to an elevation to be picked up and wrapped around the can as 20 the can rolls over the label. The feeding mechanism being separate and apart from the invention herein, no disclosure thereof is made, as the same may be of a construction well known and common in the art. 25

30 The parts of the machine heretofore described are all substantially the same as those in an existing commercial machine, and, therefore, may be regarded as of old structure, with the function and operation well-known, the introduction thereof as herein made may be regarded as sufficiently clear and ample for the purposes herein required, and it may also be understood that suitable power means are provided for transmitting motion to the carrier belts 9, 9, through one of the shafts and pair of pulleys 8.

Can gluing mechanism.

50 Below the rails 10, 10, in advance of the label table, a paste or glue holding reservoir 16 is supported upon the frame within which a glue applying or distributing roll 17 is revolved. The glue or adhesive distributing roll 17 has its periphery provided with a series of annular grooves and thereby forms a series of spaced annular ribs which engage with and distribute the glue upon the periphery of the can 18 diametrically disposed above the roll 17. A peripherally grooved or ribbed roll avoids an application of an excessive quantity of glue upon the can periphery, and represents a preferred type of roll, although its peripheral surface may follow various designs

of ribbing or roughening most adapted for efficient distributing or spreading of the glue upon the can and which will apply the glue around the can at the cover joint for effectively securing the label to the can over the 70 cover. In fact, the glue distributing rolls now commonly employed in the commercial can-labeling machines can be used.

The can after it has been released from the delivery tray 12 by time controlled delivery mechanism, not shown, or as it may be manually released by the operator, travels by gravity forwardly over the rails 10, 10, until it is engaged by the lower forward runs of the carrier belts 9, 9, from whence 80 it is conveyed or rolled by belts through their frictional contact upon the peripheral edge of the can. The can continues in its travel upon the rails until it strikes against the stop arm 19 on the rock shaft 20 journaled in bracket journals depending from the carrier frame. The stop arm 19 is located at a point or station in the can travel which will hold the can diametrically above and upon the glue distributing roll 17. The 90 periphery of the glue distributing roll 17 is slightly above the plane of the track rails for raising the can off of the rails, while the periphery of the can is being coated with glue. This relieves the can from any friction imparting a force counter to the direction of the can rotation and also increases the frictional grip between the can and belts for revolving the can upon the rotating glue distributing roll. The glue 100 distributing roll likewise is rotated in an appropriate direction to assist, with the belts, in transmitting rotary motion to the cans, although rotating at a different rate of speed from that of the belt, which produces a wiping action upon the can periphery as may be distinguished from a rolling action, one with the other, for the purpose of depositing a thin film of glue upon the can. This differentiation in speed offers a 110 control as to the quantity of glue applied to the can. The carrier belts 9, 9, at points in front and in rear of the can gluing station, travel over guide rollers 21, 21, respectively journaled upon journal brackets 115 22, 22, depending from the carrier frame. These guide rollers permit such portions of the belt therebetween to be spanned when engaged by a can to increase its frictional grip upon the can.

120 As shown in the drawing, the belt is spanned to such a degree, so that such portion of the belt extending beyond the can edge will lap over and against the ends of the can, exerting an increased force, and together with the opposite belt operating similarly, impart a compressing influence against the can ends, tending to force the cover upon the can body before the label is applied.

The glue distributing roll 17 is mounted upon a shaft or spindle 23, suitably journaled with the side walls of the glue reservoir. On one end of the shaft 23 a pulley 24 is fixed, which pulley is engaged by a belt 25 engaging with a pulley 26 fixed on a shaft 27 journaled in the carrier frame. The shaft 27 is provided with a second pulley 28 engaged by a belt 29, and the belt 29 is engaged over a pulley 30 fixed upon the shaft 7, for the carrier belt pulley.

The can after its periphery has been suitably coated with glue, and after it has made one complete revolution at its gluing station, is released by raising the stop arm 19. The arm is automatically raised by a successive can advancing toward the glue roll and through the following instrumentalities:—

32 indicates a lever arm fixed on the rock shaft 20 and pivotally connected with a link 33. The link 33 extends forwardly and pivotally connects with a lever arm 34 fixed to a rock shaft 35, journaled in the bracket 36, extending upwardly from the main frame 2. A trip arm 37 is fixed to said rock shaft 35 and extends upwardly between and above the plane of the track rails in the path of the cans traveling over the rails. The free end of said trip arm is provided with an anti-friction roller. Thus when the roller of said trip arm is engaged by a can, the trip arm is swung downward by the can, which imparts motion to the stop arm 19 through the intermediate connection joining said arm, thereby raising the stop arm 19, freeing a glue coated can and permitting such can to continue its travel over the rails, picking up a label and folding or wrapping the label around itself. The machine may be provided with suitable brush or belt pressure means common to such type of machines.

As soon as the can has passed over and beyond the trip arm to again free the arm, it is quickly swung upward through the tension of a spring 38, one end fixed to the bracket 36 and its opposite end to an arm 39 on the rock shaft 35, and the stop arm is simultaneously lowered to stop the can after it has engaged upon the glue distributing roll 17.

For spot-gluing, the can under the well-known practice of applying labels upon cans, which are not necessary to be sealed at the cover joint, the stop arm or finger 19 is moved and sustained in a position at which it will not engage the can. This can be done by unhooking the spring 38 from the arm 39. The trip arm will then swing downward by gravity, and the course of the can will be free through the machine.

Having described our invention, we claim:—

65 1. In a can-labeling machine, a track upon

which a can to be labeled travels, a roll disposed to engage the can at a point in its travel upon the track for distributing an adhesive upon the can periphery, conveyer means for engaging the peripheral can edges 70 for revolving and advancing the can upon the track, and stop means for withholding the can travel when the same is engaged with said roll.

2. In a can-labeling machine, a track upon 75 which the can rolls, a rotative adhesive distributing roll disposed at a station to engage with the periphery of a can traveling upon the track, belts respectively engaging the opposite peripheral edges of the can revolving 80 and advancing the can upon the track, and means for arresting the can travel when engaged with said roll.

3. In a can-labeling machine, a track upon 85 which the can rolls, a rotative adhesive distributing roll disposed at a station to engage with a can traveling upon the track, means for arresting the can travel when engaged with said roll, and means for tripping said can arresting means by a successive can advancing toward said roll.

4. In a can-labeling machine, a track over 95 which the can is rolled, a rotative adhesive distributing roll, which the can engages in its travel upon the track, endless conveyer means for advancing the can upon the track and for revolving the can when engaged with said rolls, and a stop member for holding the can against advance when engaged with said rolls for applying an adhesive entirely around the can. 100

5. In a device of the character described, a rotative roll for applying an adhesive upon a cylindrical can, means for blocking any advance of the can when engaged upon 105 said roll, and a pair of belts respectively engaging opposite peripheral edges of the can for revolving said can upon said roll, whereby the adhesive may be applied upon the can around its entire periphery. 110

6. In a device of the character described, a rotative roll for applying an adhesive around the periphery of a can, when engaged with the can, means for advancing the can to peripherally engage said roll and revolve 115 the can when engaged with the roll, and means for holding said can against advance when engaged by and sustained upon said roll.

7. In a device of the character described, 120 a rotative roll for applying an adhesive around the periphery of a can, when engaged with the can, means for holding said can against advance when engaged by and sustained upon said roll, and means actuated 125 by a successive can traveling toward said roll for tripping said first-named means and releasing said can from its roll engagement.

8. In a device of the character described, 130 a track upon which a can is rolled, a rota-

tive adhesive distributing roll having its periphery above the plane of the track to engage the can and sustain the can above the track, can conveyer means for rolling 5 the can upon the track and revolving the can upon said roll, and means for arresting the advance of the can when engaged with said roll.

9. In a device of the character described, 10 a track upon which a can is rolled, a pair of endless belts engaging the periphery of the can respectively at its ends for advancing the can upon the track, a rotative adhesive distributing roll in the can track path 15 for engaging said can, means engaging said belts and coöoperating with the can when

engaged with said roll for increasing the belt grip upon the can and flexing a portion of the belt on the can ends for exerting an inward pressure upon the can, adapted to 20 force the can cover upon the can body, and means for arresting the advance of the can when engaged by said roll.

In witness whereof, we hereunto subscribe our names, as attested by the two subscribing witnesses.

FREDERICK T. VON WAHLDE.
